(57) **CLAIM**

The ornamental design for a trunk, as shown and described.

DESCRIPTION

FIG. 1 is a front, right side perspective view of a trunk, showing my new design;

FIG. 2 is a rear, left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of a portion 9 in FIG. 1; and,

FIG. 10 is an enlarged view of a portion 10 in FIG. 1.

The broken lines in FIG. 4 depict portions of the trunk that form no part of the claimed design, and the broken lines in FIGS. 1, 9 and 10 are for the purpose of depicting the cut line of the enlarged views and form no part of the claimed design.

1 Claim, 10 Drawing Sheets
